CONTAINER FOR CYLINDRICAL OBJECTS

Robert E. Jones, Jr., Colorado Springs, Colo., assignor to
Kaman Aircraft Corporation, Bloomfield, Conn., a cor-
poration of Connecticut

Filed Nov. 20, 1964, Ser. No. 82,727

Term of patent 14 years

(Cl. D58—17)

FIG. 1.

FIG. 3.

FIG. 2.

FIG. 4.

FIG. 5.

FIGURE 1 is an isometric view of a container for cylindrical objects showing my new design;

FIGURE 2 is a side elevational view with the cap removed;

FIGURE 3 is an end view looking from the left of FIGURE 2;

FIGURE 4 is a side elevational view of the cap portion; and

FIGURE 5 is an end view looking from the right of FIGURE 4.

I claim:

The ornamental design for a container for cylindrical objects, as shown.
